ALFRED J. MORROW, OF OAKLAND, CALIFORNIA.

PAPER TRUCK.

Application filed February 16, 1927. Serial No. 168,621.

This invention relates to improvements in warehouse trucks and particularly to improvements in trucks for handling rolls of news print paper.

Explanatory to the invention, I will state here that there is an enormous loss caused by the now commonly employed methods and means of handling news print paper. This loss results from damage done to the edge of the rolls of paper during the loading or unloading process. This will be better understood when it is known that such rolls of paper weigh from twelve to fifteen hundred pounds and when they are tilted over on the edge for loading onto or from a truck, this enormous weight mashes or breaks the edge of the roll. Should a roll of paper that is so damaged be placed in a printing press, the strip of paper will tear, due to the stress placed thereon, at the damaged place and as a result the press will have to be stopped and the strip re-threaded through it. For this reason, it is customary for a press man to inspect each roll before it is placed in the press and to cut away the roll down to the depth of any damaged edge portion. This may necessitate the removal of the outer part of the roll to a depth of from one-fourth inch to one inch and this, in a short length of time, runs into an enormous amount of waste.

In view of the above, it has been the principal object of this invention to provide improvements in trucks which permits the loading, or unloading of rolls of news print paper therefrom without placing the weight of the roll on the edge and, in this way, avoids damage to the roll that would require any of the paper to be wasted.

More specifically stated, the principal feature of the invention resides in the details of construction and manner of mounting the nose of the truck by means of which the paper roll is supported.

Another object of the invention is to so construct the frame of the truck and to so locate the supporting wheels thereon that rolls of different length may be carried in proper balance that their weight is not sustained by the operator in handling or moving the truck.

Other objects of the invention reside in the various details of construction and combination of parts as will hereinafter be described and in their mode of operation.

In accomplishing these objects, I have provided the improved details of construction,

the preferred forms of which are illustrated in the accompanying drawings, wherein—

Figure 1 is a side view of a paper roll handling truck embodied by this invention; 60 showing it in the initial position in loading a paper roll thereon.

Figure 2 is a view showing the roll loaded thereon.

Figure 3 is a vertical section of the truck 65 nose.

Figure 4 is a plan view of the lower end of the truck.

Figure 5 is a perspective view of a nose of an alternative type of construction. 70

Referring more in detail to the drawings—

1 and 2 designate spaced apart handle bars of the truck frame. These are provided at their upper ends with suitable hand holds 3 and at their lower ends are cut on a bevel, as 75 at 4, so that when the handle bars extend upward at an angle of approximately sixty degrees with the horizontal, the ends rest flatly against the floor. The bars 1 and 2 are rigidly joined by a plurality of transverse bars 5 and by an axle 6 fixed thereto beneath their lower end portions. This axle is provided at its ends with supporting wheels 7—7 which would be sufficient width and diameter to provide easy movement. 80

Toward the upper ends, the handle bars have downwardly extending frames bolted thereto. These comprise spaced apart side pieces 10—10' and transverse connecting pieces 11 and 12. Caster wheels 13 are mounted by standards 14 which extend revolubly through apertures in the cross pieces and which are supported thereon by short cross plates 15 that are pivotally mounted by pins 16 within slots 17 provided in the standards. 90

The standards are fixed at their lower ends to yokes 18 which mount the caster wheels and the head of the yoke of each wheel rests in supporting engagement with the lower cross piece 12 of its frame. The caster 100 wheels ordinarily would be used only when long rolls of paper which extend well toward the ends of the handles are being moved.

When short rolls are handled the casters are detached by turning the cross plates 15 longitudinally of the standards and then withdrawing the standards from their frames. 105

The frames may then be used as supporting legs when the truck is at rest.

The principal feature of this invention resides in the details of construction of the nose. 110 This comprises an upright plate 20 that is

curved transversely at approximately the same curvature as the side surface of the rolls of paper to be handled by the truck, and it terminates at its upper edge in a rearwardly curled lip 21 and adjacent its lower edge at opposite sides has ears 22 fixed thereto through which pivot bolts 23 are extended to pivotally attach it to ears 24 on straps 25 fixed to the lower ends of the handle bars, thus adapting the top of the plate to tilt toward or from the handle bars.

Supported horizontally at the lower edge of the plate 20 is a shoe 28 which has a short upstanding flange 29 at its rearward edge that is alined with and corresponds to the curvature of the plate 20. This shoe is adjustably attached to the plate 20 by means of two bolts 30 and 30' which are fixed at their lower ends in lugs 31 on the back side of the flange 29 near the ends of the shoe 28 and at their upper ends are slidably mounted in lugs 32 fixed to the back side of plate 20. On the upper ends of the bolts are nuts 33 which may be adjusted to different position to limit their downward travel by contact with the lugs 32. This connection provides a rigid mounting for the shoe but permits it to move toward the lower edge of plate 20 for loading and away from it to afford better balance of the roll in transportation.

The shoe plate is of substantial width and is provided, in parallel spaced relation, to the rear edge flange 29, with an upwardly pressed shoulder 35 as shown best in Figure 3. This shoulder is formed approximately one and one-half inches from the flange 29 and one-fourth inch above the flat base portion of the plate between the flange 29 and shoulder. When the truck is positioned for loading a roll of paper, it is placed as shown in Figure 1 and in order that the forward edge of the shoe will be held down against the floor in such position that it may be slipped beneath the roll to be loaded and may not tip back and be gouged into the side of the roll as often happens when loosely hinged, I have fixed rearwardly extending arms 38 to the rear of the flange 29 of the shoe and have attached springs 39 to the ends of these arms and to the bars 1 and 2. These springs are of sufficient strength to hold the plate 28 against the floor during loading but do not interfere with movement of the shoe away from the plate 20 after the roll of paper is positioned thereon.

In Figure 5 I have illustrated a nose construction of an alternative type wherein the back plate 20' and shoe 28' are formed in an integral piece. This is provided with mounting ears 22' which are attached to the truck in the same manner as the plate previously described. The shoe piece is likewise provided with the raised shoulder 35 as is the piece 28.

It is also desirable to have a locking dog 65 49 pivotally mounted on the axle and adapted to be pressed into holding contact with the floor to prevent back movement of the truck when the roll is being tilted onto it and to assist in prying rolls of paper into place. 70 This dog may be weighted so as to automatically lift from the floor when pressure is placed thereon.

Assuming the truck to be so constructed, it would be used as follows: 75

When a paper roll is to be loaded, the truck is moved up to the roll, which stands on end, and the handles of the truck are extended upwardly so that the lower ends of the bars 1 and 2 rest flatly on the floor and the shoe plate 28 is held against the floor by springs 39. First, the paper roll is tilted just enough to permit the shoe to be projected beneath it and the side of the roll to be seated against the flange 29 of the shoe and against the plate 20. It will be noted, by reference to Figure 3, that when the paper roll is in this position, it is supported on the shoe at a point approximately one and one-half inches inside of its edge, and the edge is not in contact with any support by which it could be damaged when the roll is tilted back onto the truck. The roll is then tilted back against the truck handles and the truck then tilted down, so as to assume the position shown in 95 Figure 2. It is to be pointed out that during this tilting movement of the roll and truck the shoe 28 remains on the floor until the bolts 30 have extended to their limit of travel and thus the roll, if it is the longer type of 100 roll, is permitted to come near to a balance over the supporting axle. If the roll is a short one, the caster wheels are not desired for the reason that the center of gravity of the roll is forward of the supporting axle and 105 can only be shifted rearwardly thereof by tilting the handles down farther than is permitted when the casters are used. Therefore, the casters should be removed and this can be done quickly by turning the keys 15 with 110 in the slots 17 so that the standards 14 may be withdrawn; if the roll is a long one, the casters are desired to support the rear part of the truck, as shown in Figure 2.

By use of a truck having a supporting 115 shoe of this character, the edge of the paper roll which otherwise is damaged, does not come in supporting contact with the base of the shoe in loading and this insures that it cannot be mashed or damaged as is usually 120 the case when loaded onto or pried about by the ordinary type of blunt nosed trucks. When no damage is done to the edge of the roll there is no waste of paper. Such trucks may be made in various sizes, and for various 125 purposes, and its details of construction may be altered without departing from the spirit of the invention.

Having thus described my invention, what I claim as new therein and desire to secure by Letters-Patent, is:

1. A truck of the character described comprising a frame, a transverse axle, supporting wheels on the axle and a nose pivotally attached to the lower end of the frame on which a roll of paper may be supported for transportation, said nose comprising an upright, transversely curved back plate adapted to embrace the side of the roll and a forwardly extending base plate adapted to project beneath the end of the roll, mounting bolts rigidly fixed thereto and extended slidably through mounting lugs fixed to the back plate and permitting the base plate to move toward the lower edge of the back plate during a loading operation and to move away from the plate when the roll is tilted back onto the truck as a means of bringing the center of gravity of the roll toward the vertical plane of the supporting axle.

2. A truck of the character described comprising a frame, a transverse axle at the lower

end of the frame, supporting wheels on the axle, a nose pivotally mounted at the lower end of the frame on which a roll of paper may be supported for transportation, said nose comprising an upright, transversely curved back plate adapted to embrace the side of the roll and a forwardly extending base plate adapted to project beneath the end of the roll, mounting bolts rigidly attached to the base plate and having their upper portions slidably mounted in mounting lugs on the back plate, whereby the base may move from and toward the lower edge of the back plate, means on the bolts for adjustably limiting their extension, and yieldable means attached to the nose and to the frame whereby the base plate will be urged yieldingly downward, said base plate having an upwardly offset shoulder formed arcuately thereon adapted to supportingly engage the end of the roll at a distance within its peripheral edge.

Signed at Seattle, Washington, this 24th day of December, 1926.

ALFRED J. MORROW.
